CIRCUIT-INTERRUPTING MECHANISM

Application filed January 27, 1927. Serial No. 163,913.

My invention relates to circuit interrupters and particularly to operating mechanisms therefor.

One object of my invention is to provide a circuit-interrupter operating mechanism that may not be held closed when abnormal conditions exist.

Another object of my invention is to provide a circuit interrupter with a closing mechanism that shall be released when tripped at any one of its positions.

A further object of my invention is to apply an operating mechanism to circuit-interrupter cover plates for panels that shall be "trip-free" in all of its operating positions.

Heretofore, it has been the practice to employ a separable closing mechanism for circuit interrupters to be actuated by a tripping mechanism when the circuit interrupter nearly reaches its closed position. The closing of the main contact members of the circuit interrupter, under conditions of an overload or short circuit, causes pitting of the main current-carrying parts and, where the circuit interrupter is not completely brought to closed position, it can be held closed against a condition of overload or short circuit, thereby not only endangering the apparatus in question but adjoining apparatus and the life of the operator.

According to my invention, I am able to release the operating mechanism, at any position of its closing movement, upon the actuation of the tripping mechanism by a predetermined electrical condition. This makes the apparatus entirely dependable in its operation and safe.

In the accompanying drawing, Figure 1 is an elevational view of a circuit interrupter and of the closing and tripping mechanism therefor, with a supporting panel and cover plate shown in section; and

Fig. 2 is a schematic view showing the details of the various elements of the closing and tripping mechanism shown in Fig. 1.

My invention comprises, in general, a circuit interrupter 1 that may be any switch mechanism requiring a horizontal or vertical movement to close its electrical contacts, that is linked to a closing mechanism 2 by a pull

rod 3. A panel 4 of insulating material has secured thereto the circuit interrupter 1 and a cover plate 5 that supports the closing mechanism 3 and a tripping mechanism 6.

The closing mechanism 3 is manually operated and comprises an operating handle 7 having a spring-biased latch 8 that supports a roller 9 by a pin 10 for engaging one end of a closing lever 11 at a notch 12, whereby the operating handle 7 and the closing lever 11 are united as one lever. The pin 10 on the latch 8 extends through a slot 14 in a link 15 that is loosely pivoted upon a shaft 16. The link 15 contains a slot 17 through which extends a pin 18 that is mounted on a link 19 that is connected to a tripping bell-crank 20 having a counter weighted portion 21 for imparting a movement therefrom to the roller 9 for tripping the circuit interrupter at any one of its positions. The tripping bell-crank 20 is actuated by an armature 22 of the tripping mechanism 6.

A latch 24 engages a catch 25 mounted on the operating member 7, thereby latching the circuit interrupter 1 in the closed position until it is released therefrom by a manually operated push rod 26 or by the excitation of the tripping mechanism 6.

Assuming the parts be in the circuit closing positions shown in Figs. 1 and 2, with the handle 7 held in its lower position by the cooperation of the latch 24 and the catch 25, and it is desired to manually open the circuit interrupter 1, the operator presses upon the end of the rod 26 which serves to push the latch 24 from off the end of the catch 25. Thereupon, the handle 7 is pulled upwardly by reason of the pressure exerted by the pull rod 3 upon the shaft 16. The operating handle 7, moving upwardly, carries with it the latch 8, the pin 10, the roller 9, the link 15 and the closing link 11. During this movement, the angular relation between the links 15 and 19 varies by reason of the movement of the pin 18 in the slot 17.

In order to reset the circuit interrupter, the operating handle 7 is again pulled downwardly until the latch 24 engages the catch 25.

In order to automatically trip the circuit interrupter 1, the tripping mechanism 6 is 100

electrically energized in accordance with any desired electrical conditions, such as conditions of overload or of short circuit. Whereupon, one or more of the armatures 22 will move upwardly and impart a counter-clockwise turning movement to the bell-crank 20.

The bell-crank 20 is suitably weighted to take up all the back lash that exists between the linking elements. That is, the weight ex-

erts a force on the link 19, causing the attached pin 18 to bear against the inner face of the slot 17 and thereby move the link 15 until the near face of the slot 14 engages the pin 10, whereby a light blow from the armature 22 upon the bell-crank 20 will be imparted directly through the levers to the roller 9 and will not be absorbed by the movement in the lever system to take up the back lash and thereby fail to trip the circuit-interrupter.

The actuation of the armature 22 imparts a movement from the bell-crank 20 to the link 19 through the pin 18 to the rear of the slot 17 to the link 15, thence from the rear of the slot 14 to the pin 10 that operates the roller 9, moving it from the notch 12 in the lever 11, and the latter is freed to permit the pull rod 3 to move downwardly. The slot 14 in the link 15 is provided to allow the roller 9 and the pin 10 to move freely as soon as the roller is over center on the edge of the notch 12.

During the outward movement of the pin 10, a coil spring constituting a portion of the latch 8, is tensioned in order to cause the roller 9 to return to its initial position after the release of the closing lever 11.

In order to reset the circuit interrupter 1, the operator presses on the rod 26 and thereby releases the operating handle 7 from the latch 24. The operating handle 7 is then raised upwardly, carrying with it the latch 8 and the link 15 until the roller 9 engages the under face of the closing lever 11. Thereafter, the roller 9 moves over the end of the closing lever 11 and is seated in the notch 12 by reason of the tension of the spring on the latch 8. The operating handle 7 is then depressed, carrying with it the closing lever 11 until the latch 24 again engages the catch 25, thereby closing the circuit interrupter 1. The foregoing cycle of operations may be repeated indefinitely and in any order that may be desired.

It is to be observed that, in all positions of the operating mechanism 2, the link 19 remains in a horizontal position and is subject to actuation by the operation of the trip mechanism 6. Since the link 15 is permitted to have angular motion with respect to the link 19 and, at the same time, is subject to actuation by the pin 18 mounted on the link 19, it follows that an actuation of the tripping mechanism 6 at any time will result in the movement of the roller 10 out of engagement

with the notch 12, thereby insuring that the circuit interrupter 1 will be tripped, regardless of the position of the operating handle 7.

Accordingly, I have devised an operating mechanism for circuit interrupters that is adapted to be supported on a cover plate for mounting on a panel, pipe frame or other supporting means, which mechanism permits the release of a connected circuit interrupter at any one of its positions.

It is to be understood that such changes in the form, arrangement, and connection of the component parts of my invention may be made as shall fall within the scope of the appended claims.

I claim as my invention:

1. The combination with a circuit interrupter supported on the rear of a panel, of a tripping mechanism mounted on a cover-plate secured to the front of the panel, an operating member comprising separable elements, a latching means for uniting the separable elements, and a lever system connected to the latching means and to the tripping mechanism.

2. The combination with a circuit interrupter and a tripping mechanism, of an operating member comprising separable levers, latching means for uniting the levers, and a pair of associated levers connected to the tripping mechanism and to the latching means, in such manner that the tripping mechanism controls the latching means in all positions of the operating member.

3. The combination with a circuit interrupter and a tripping mechanism, of a separable operating member having means for uniting its separable elements, means for joining the tripping mechanism to the uniting means in such manner that a tripping movement can be transmitted to the uniting means at all positions of the operating members.

4. The combination with a circuit interrupter and tripping mechanism, of an operating member composed of separable levers, latching means in the operating member for uniting the levers, and a pair of adjacent levers flexibly united at one end and having their other ends attached to the tripping mechanism and latching means, respectively, in such manner that one of the levers follows the movement of the operating member and constitutes the means for transmitting an impulse from the tripping mechanism to the latching means at any position of the operating member, whereby the release of the separable levers of the operating member permits the circuit interrupter to be opened at any position in its closing movement or in its closed position.

5. The combination with a circuit interrupter, of an operating member therefor comprising separable members, latching means for uniting the separable members, a tripping

mechanism, and means disposed within the operating member to enable the tripping mechanism to separate the operating member at any of its positions.

5 6. The combination with a circuit interrupter, of a supporting panel, a cover-plate therefor, an operating member and a tripping mechanism disposed on said cover-plate, a lever system disposed within the operating member comprising two adjacent members loosely pivoted upon a shaft and flexibly connected to each other, having one end of one of the members connected to the tripping mechanism and an end of the other member connected to the latching means in such manner that, in any one of its positions, an impulse from the tripping mechanism will be carried by the lever system to the latching means, whereby the operating mechanism will be separated from the circuit interrupter.

10 7. The combination with a circuit interrupter, of a supporting panel, a cover-plate therefor, a separable operating member, a latching means and a tripping mechanism disposed on said cover-plate, and a lever system comprising two adjacent members connected to the tripping mechanism, to the latching means, and to each other.

15 In testimony whereof, I have hereunto subscribed my name this 20th day of January, 1927.
